United States Patent Office

Des. 192,101
Patented Jan. 16, 1962

192,101

COMPOUND HAND TOOL

Maynard H. Brown, Jr., Herkimer, N.Y.
(East Herkimer, N.Y.)

Filed Nov. 10, 1960, Ser. No. 62,793

Term of patent 14 years

(Cl. D54—13)

FIG. 1

FIG. 2

FIG. 3

FIG. 4

FIGURE 1 is a top plan view of a compound hand tool embodying my new design;

and

I claim:

The ornamental design for a compound hand tool, as shown.
